UNITED STATES PATENT OFFICE

HORTON J. PETERSON, OF EVELETH, MINNESOTA

CABLE TERMINAL SHIELD

Application filed February 13, 1930. Serial No. 428,212.

This invention relates to safety terminal connections for electric meters, and refers particularly to novel means for assuring against the theft of current adjacent the terminal connections of such meters, the principal object of which is obvious, and another object being that of providing a simple insulating shield adjacent an electric wire terminal.

10 Other objects and advantages of the invention will appear in the following description thereof.

Referring now to the accompanying drawing, wherein like reference characters indicate like parts:

Figure 1 is a plan view of the terminal chamber of an electric meter showing the feed wire terminals to the meter as being equipped with the insulated tip, one of which 20 is shown in section; and

Figure 2 is a perspective view of a disassembled tip and wire.

1 represents the terminal chamber of the meter which is provided with the usual four 25 terminal flanged sockets 2 for the input and output connections.

It is well known that the electric current to such meters is frequently bypassed by a short piece of wire being tucked into one of 30 the flanged sockets 2 at one end and into the socket 3 at the opposite end so as to engage the unshielded portion of the wire in such sockets.

In the ordinary construction of meter such 35 unauthorized practice becomes very simple as there is invariably space about the end of the insulation of such wires for readily slipping a shunt wire into the socket where it is readily held by impingement against 40 that portion of the terminal wire which is uninsulated.

To prevent such practice I have provided 45 preferably a glass shield of thimble-like form indicated at 4 though of course this may be made of other non-conductive material, but 50 glass has the added advantage of being readily detected if fractured or broken for such practice; the same to fit snugly over the wire being used for feeding current into the 55 meter. A hole 5 is provided in the end of

the shield 4 for protrusion of the naked portion 6 of the wire, or that from which the insulation has previously been removed, so that no alteration in the meter chamber is required, however the shield 4 is of a size to 55 snugly fit within the annular flange 2 or 3 provided about such terminal connections. The shields are of sufficient length to extend considerably beyond the flanges of the chambers so that it becomes practically impossible 60 to insert a wire through or past the insulation as commonly practiced without breaking the terminal shield.

I am aware that somewhat similar appearing terminals are old in the art but are formed 65 in cooperative combination with a novel form of conductor needle or point, they being for the purpose of increasing and assuring positive conductivity, and in no instance showing an insulated shield as that contemplated in my present invention. 70

Having thus described my invention, what I claim and desire to secure by Letters Patent, is:

1. The combination with an electric meter 75 casing having a plurality of flanged terminal sockets formed therein through which the supply wires make contact with the meter, of an elongated breakable thimble-like shield snugly fitting over the end of the insulation 80 of the supply wire and tightly fitting the socket, said thimble having a substantially flat end provided with a hole through which a bared end of the wire may pass with a snug fit. 85

2. In combination, a meter terminal housing having flanged cup-like holes for the reception of the feed wires to the meter and a fragile insulating thimble having a substantially flat end upon the wire terminals, said thimbles fitting snugly into the cup-like holes and tightly over the insulation of the wire, and having a hole in said end through which only the bared portion of the feed wire passes with a snug fit for making contact with the meter. 90

3. The combination with an insulated electric feed wire, the insulation adjacent the end thereof having been removed for making an electrical contact, of an elongated frangible 95 100

thimble having a substantially flat end provided with a hole therethrough; said thimble being adapted to snugly fit over the insulation and the bared portion of the wire passing through the hole with substantially a snug fit.

In testimony whereof I affix my signature.
HORTON J. PETERSON.
